UNITED STATES PATENT OFFICE.

LEON W. ROSENTHAL, OF NEW YORK, N. Y., AND GUSTAVE J. LANG, OF WEEHAWKEN, NEW JERSEY, ASSIGNORS, BY MESNE ASSIGNMENTS, TO AMERICAN BOSCH MAGNETO CORPORATION, OF NEW YORK, N. Y., A CORPORATION OF NEW YORK.

ELECTRIC IGNITION APPARATUS.

Application filed October 1, 1918. Serial No. 256,460.

To all whom it may concern:

Be it known that we, LEON W. ROSENTHAL, a citizen of the United States, residing at 106 Central Park west, in the city, county, and State of New York, and GUSTAVE J. LANG, a citizen of the United States, residing at 849 Boulevard east, Weehawken, in the county of Hudson and State of New Jersey, have invented certain new and useful Improvements in Electric Ignition Apparatus; and we do hereby declare the following to be a full, clear, and exact description of the invention, such as will enable others skilled in the art to which it appertains to make and use the same.

The present invention relates to electric ignition apparatus for simultaneously producing sparks at two or more spark plugs in a cylinder of an internal combustion engine, or in a plurality of cylinders in turn, from two or more magnetos and more particularly it comprehends the use of apparatus for this purpose comprising a single mechanical interrupter for simultaneously altering the circuits of two or more magnetos, and suitable means for conducting to the respective spark plugs the ignition currents generated therein.

In internal combustion engines having comparatively large cylinders, it is now usual to provide more than one spark plug in each of the cylinders, in order that the flame propagation be accelerated throughout the combustible mixtures and the combustion made more complete thereby in each working stroke. Heretofore, this was sometimes accomplished by connecting two spark plugs in a cylinder in electrical series and producing the sparks at both from a single source, but where a single magneto was used for this purpose, difficulty arose on account of the increased voltage generated in the magneto. In another prior arrangement, two independent magnetos were used, but in that case, a slight variation in the timing or in the wear or setting of the driving gears, or of the operating parts of the interrupter, caused the sparks to occur successively instead of simultaneously, with the result that the second spark is useless, or practically so, especially when the engine operates at high speed or has many cylinders.

In accordance with our invention, these

difficulties are overcome and the construction simplified in apparatus embodying a plurality of magnetos, by providing a single mechanical interrupter using either a single cam member and for each magneto a pair of interrupter elements connected directly thereto and operated simultaneously by the cam member, or else a single cam member and a single pair of interrupter elements for all the generating winding which are connected in parallel or series, or series parallel with each other; the magnetos being arranged to operate in synchronism, that is, in phase with each other. In this way, the circuits of all the magnetos are altered, that is opened, closed or grounded, at the same instant, and thus sparks are produced at the same instant at all of the spark plugs in each cylinder, irrespective of the timing adjustment of the interrupter, and of any usual variation due to setting or wear of the driving gearing. In any of these arrangements, the distributors for a multi-cylinder engine may be incorporated with the respective magnetos or they may be mounted on a common shaft or on independent shafts driven at cam shaft speed for 4-cycle engines. The mechanical interrupter may be mounted on a separate shaft driven by the engine at the same or a different speed from that of the magnetos, or directly on one or the other of the magneto shafts, the circuits of the magnetos being altered by the mechanical interrupter at substantially the periods of their maximum generation.

In the accompanying drawings illustrating several embodiments of our invention in application, as an example, to a 12-cylinder 4-cycle engine having two spark plugs in each cylinder, wherein the mechanical interrupter is mounted on an operating shaft to which two high tension magnetos are independently geared, and rotates at the same speed as the magnetos, and wherein the two distributors are mounted on the cam shafts of the engine, Fig. 1 is a front elevation of the engine showing the ignition apparatus installed thereon; Fig. 2 is a front view of the mechanical interrupter of Fig. 1 having a single pair of interrupter elements; Fig. 3 is a front view of a modified form of mechanical interrupter having two pairs of interrupter elements; and Fig. 4

is a wiring diagram for the mechanical interrupter of Fig. 2.

Referring to Fig. 1, the engine 1 has cylinders 2 arranged in V and has a crank shaft 3 driving an operating shaft 4 through 1:1 $\frac{1}{2}$ speed-increasing bevel gearing 5. The mechanical interrupter 6 is mounted on the operating shaft 4 and the two magnetos 7, each producing four ignition currents per rotation, are driven at the speed of the operating shaft through 1:1 bevel gearings 8. The distributors 9 are mounted on respective cam shafts of the engine and are arranged to simultaneously distribute high tension ignition current from the magnetos 7 to respective spark plugs 10 of each cylinder in turn.

As shown in Fig. 2, the mechanical interrupter of Fig. 1 has a single cam member 11, with four cam portions 12, fast with the operating shaft 4. There is a single pair of interrupter elements, comprising the deflectable element 13 cooperative with the cam member to be separated thereby from the normally stationary interrupter element 14 at four equally spaced intervals per rotation of the operating shaft corresponding to the four angular positions of maximum generation of the magnetos 7. As shown in Figs. 1 and 4, the insulated terminals of the primary windings 15 of the two magnetos are connected in electrical parallel by the wires 16 to the interrupter element 14, whereas the secondary windings 17 are connected by the wires 18 to the respective rotatable brushes 19 of the distributors 9.

At each period of ignition, the interrupter element 13 is separated from the element 14 by the cam member 11, thereby removing the common ground connection 20 from the circuits of both of the primary windings 15. Thus, since the two magnetos 7 are synchronized, the alteration of the circuits of the primary winding thereof has substantially the same effect as if those circuits were individually interrupted. Accordingly, ignition voltages are simultaneously produced in the secondary windings 17 of the two magnetos at each period of ignition, and the secondary currents resulting therefrom are conducted through the respective distributors to independent spark plugs of each cylinder in turn.

In Fig. 3, two pairs of interrupter elements are substituted for the single pair of Fig. 2, but the two deflectable elements 21 are simultaneously separated from the normally-stationary elements 22 by the same cam member 11. Although this arrangement permits independent connection of the two primary windings of the magnetos 7, and actually interrupts those circuits at each period of ignition, it may have the disadvantage over the single pair of interrupter elements that in case the fibre blocks 23 should

wear to different extents, the sparks at the two spark plugs of each cylinder would not occur at exactly the same instant although they would occur substantially simultaneously notwithstanding any usual amount of unequal wear of the driving gearings 8.

It will be understood, of course, that the mechanical interrupters may be adjustable in any suitable way, as for instance, by turning the housing 24 around the operating shaft. The sparks from the two magnetos will occur simultaneously for any adjustment, even if the rotating members of the two magnetos 7 would be set or should become by wear slightly displaced from similar angular positions at each or all of the ignition periods.

Having described our invention what we claim is:

1. The combination with an internal combustion engine having a cylinder with two spark plugs and also having an operating shaft driven by it, of electric ignition apparatus for producing sparks at the spark plugs simultaneously, comprising two magnetos driven in synchronism with each other by the operating shaft, a single mechanical interrupter driven by the operating shaft and constructed and arranged to simultaneously alter the circuits of the two magnetos and produce ignition currents therein, and means for conducting the ignition currents to the respective spark plugs.

2. The combination with an internal combustion engine having a cylinder with two spark plugs and also having an operating shaft driven by it, of electric ignition apparatus for producing sparks at the spark plugs simultaneously, comprising two magnetos geared to the operating shaft to run synchronously with each other, a single mechanical interrupter driven by the operating shaft and constructed and arranged to simultaneously alter the circuits of the two magnetos and produce ignition currents therein, and means for conducting the ignition currents to the respective spark plugs.

3. The combination with an internal combustion engine having a cylinder with two spark plugs and also having an operating shaft driven by it, of electrical ignition apparatus for producing sparks at the two spark plugs simultaneously, comprising two magnetos geared to the operating shaft to run synchronously with each other, a single mechanical interrupter driven by the operating shaft and constructed and arranged to simultaneously alter the circuits of the two magnetos and produce ignition currents therein, and means for conducting the ignition currents to the respective spark plugs, the two magnetos being connected to the mechanical interrupter in electrical parallel.

4. The combination with an internal combustion engine having a cylinder with two

- spark plugs and also having an operating shaft driven by it, of electric ignition apparatus for producing sparks at the spark plugs simultaneously, comprising two magnetos independently geared to the operating shaft run synchronously with each other, a single mechanical interrupter mounted on the operating shaft and constructed and arranged to simultaneously alter the circuits of the two magnetos and produce ignition currents therein, and means for conducting the ignition currents to the respective spark plugs.
5. The combination with an internal combustion engine having a plurality of cylinders each with two spark plugs and also having a cam shaft and an operating shaft driven by the engine, of electric ignition apparatus for producing sparks at the two spark plugs of each cylinder, simultaneously, comprising two magnetos geared to the operating shaft to run synchronously with each other, a single mechanical interrupter driven by the operating shaft and constructed and arranged to simultaneously alter the circuits of the two magnetos and produce ignition currents therein, and two independent distributors mounted on the cam shaft to conduct the ignition currents to the respective spark plugs of each cylinder in turn.
